UNITED STATES PATENT OFFICE.

CHARLES LOUIS BERNIER, OF SANTA ANA, CALIFORNIA.

DISPENSING CONTAINER.

Application filed May 27, 1924. Serial No. 716,248.

To all whom it may concern:

Be it known that I, CHARLES L. BERNIER, a citizen of the United States, and resident of Santa Ana, in the county of Orange and State of California, have invented certain new and useful Improvements in Dispensing Containers, of which the following is a specification.

My invention is an improvement in dispensing containers of the type adapted to receive granular substances, such as sugar, and it consists in the combinations, constructions and arrangements herein described and claimed.

An object of the invention is to provide a container of the character described which affords facilities for dispensing approximately the same quantity of a granular substance at each operation thereof without there being any necessity of uncovering the container or making use of a spoon or like article to remove the contents of the container.

A further object of the invention is to provide a container of the character described which is thoroughly sanitary, in that the parts thereof can be quickly, easily and effectually cleaned and the contents of the container are protected from foreign matter, such as dirt, dust and dampness as well as from insects.

Other objects and advantages will be apparent from the following description, considered in conjunction with the accompanying drawings, in which—

Figure 1 is a view partly in side elevation and partly in vertical section, showing a container embodying the invention,

Figure 2 is a view similar to Figure 1 but taken at right angles to the latter,

Figure 3 is a section along the line 3—3 of Figure 1,

Figure 4 is a longitudinal vertical section through the measuring and dispensing apparatus of the container, showing in side elevation the fragmentary portion of a rock shaft which is associated therewith,

Figure 5 is a section along the line 5—5 of Figure 4.

A container embodying the invention comprises an upper tubular section 1, a lower section 2 which also is shown as being tubular and a removable cover or lid 3 for the upper end of the upper section 1. The upper section 1 is shown as being cylindrical in cross sectional contour and as be-

ing provided with a pair of diametrically opposite handle members 4. The lower or base section 2 is vertically disposed and is provided at its upper end with a relatively short cylindrical portion 5 having screw threads formed on the inner wall thereof for engaging with screw threads on the outer wall of the lower end portion of the upper section 1, as indicated at 6, whereby the upper and lower sections will be connected together detachably and the upper section will be supported upon the lower section. The lower section 2 preferably is formed so that the outer wall thereof will be concavely curved longitudinally of the lower section from the lower end of the cylindrical portion 5 to the opposite or lower end of the lower section.

A partition between the spaces within the upper section 1 and the lower section 2 is provided by a plate 7 which is joined integrally or otherwise at its outer edge to the lower section 2 adjacent to the upper end of the latter and preferably in the plane of the lower end of the cylindrical portion 5 of the lower section, whereby the plate 7 will provide a stop for limiting the vertical movement of the upper section 1 downwardly when the upper section 1 is screwed into the lower section and will aid in supporting the upper section. The plate 7 is substantially funnel-shaped or in other words slopes from the juncture thereof with the lower section 2 toward an opening 8 which is located at the approximate center of the plate 7.

The plate 7 thus may be termed a hopper. A measuring and dispensing apparatus which is comprised in the container includes a valve casing which comprises a cylindrical body 9 which is closed at its ends by caps or heads 10. The cylindrical body 9 of the valve casing is secured in any suitable known manner, as by means of solder, to the plate 7 so that the cylindrical body 9 will be horizontally disposed and will be positioned directly beneath the central portion of the plate 7 with an inlet opening 11 in the upper part of the cylindrical body 9 in register with the opening 8 of the plate 7. The cylindrical body 9 of the valve casing also is provided with a lateral discharge opening 12. A discharge conduit or chute 13 extends from the opening 12 in an outward and downward direction through an opening in an inwardly curved or re-entrant

portion 14 of the lower section 2 and terminates at its outer end slightly beyond the outer wall of the lower section 2 and at a level which is located approximately midway between the upper and lower ends of the lower section.

A hollow rotary valve interfits the valve casing and comprises a cylindrical body 15 which closely interfits the body of the valve 10 casing and is closed at its ends by caps or heads 16. A rock shaft 17 extends through aligned central openings in the heads or caps of the valve casing and the valve and is secured to at least one of the heads of 15 the valve in any suitable known manner, as by means of a key 18 so that rotation of the shaft 17 about its axis will cause a like movement of the valve. However, the rotary movement of the valve in the valve casing 20 is limited by means of a stop pin 19 which extends from one of the ends or caps of the valve into an arcuate slot 20 which is formed in the adjacent head or cap of the valve casing. The valve can rotate about 25 its axis only from the position best seen in Figure 4 in which an opening 21 in the body of the valve is in register with the opening 11 in the valve casing to such position that the opening 21 will be in register 30 with the lateral opening 12, or vice versa. A pull string 22 which is attached at one end to the plate 7 and at its other end to the outer end of a rocker arm 23 which is secured to the rock shaft 17 tends to hold the 35 valve within the valve casing in the position best seen in Figure 4.

The rock shaft 17 extends at one end through an opening in the lower section 2 and has the extreme outer end portion thereof 40 of squared as indicated at 24 to engage with a correspondingly configured opening in an operating handle 25. The operating handle 25 is inclined as best seen in Figure 2 at the time the opening 21 of the valve is in register 45 with the opening 11 of the valve casing. The outer end portion of the operating handle 25 preferably is flattened as indicated at 26 so that pressure tending to swing the outer end of the operating handle downwardly 50 may be conveniently applied by a finger of a hand of the user. When the outer end of the operating handle 25 is depressed, the valve will be rotated from the position shown in Figures 4 and 5 to such 55 position that the opening 21 will be in register with the opening 12. The hollow valve is divided interiorly by a diametrically disposed partition plate 27 which extends the full length of the hollow valve. The partition 60 plate 27 inclines slightly from the vertical when the opening 21 is in register with the opening 11 and is slightly inclined from the horizontal when the opening 21 is in register with the opening 12. However, the 65 end of the partition plate 27 that is located

at a level higher than that of the other end when the opening 21 is in register with the opening 11 will be located at a level lower than that of the other end when the opening 21 is in register with the opening 12.

From the foregoing description of the various parts of the device, the operation thereof may be readily understood. The upper section 1 and the cover 3 preferably are made of glass and the lower section 2 preferably 70 is made of a light gauge metal, such as aluminum. Obviously, these parts of the device may be made of other suitable material without departing from the spirit and scope of the invention. The heads or caps 80 which close the valve casing and the valve body respectively may be secured in place by solder or in any other suitable known manner and may be detachable, if desired. It of course will be understood that the 85 valve is disposed within the body of the valve casing before at least one of the heads of the valve casing is secured to the body of the valve casing.

The container is particularly well adapted for use in dispensing sugar or like granular material either in restaurants or like public places or in private dwellings. The cover 3 need not be removed after the sugar or like material is placed within the upper 90 section 1. The granular material therefore will be protected from dust, dirt, dampness and insects continuously. Material from the upper section 1 will pass by gravity through the registering openings 11 and 21 and will fill the space within the hollow valve at one side of the partition plate 27. This space is sufficiently large to accommodate a desirable and known quantity 95 of granular material. When the hollow valve is rotated about the axis of the rock shaft 17 because of manipulation of the operating handle 25, the opening 11 will be covered or closed at its lower ends by the rotating valve body as soon as the opening 110 21 is out of register with the opening 11 and will remain closed until the opening 21 is again in register with the opening 11. It will be manifest that the known quantity 115 of granular material within the hollow valve will slide by gravity on the partition plate 27 from the hollow valve to the openings 21 and 12 when the valve has been rotated to position the openings 21 in register with the opening 12 into the spout 13 120 and then through and from the latter. The receptacle into which the quantity of granular material is to be discharged may be placed directly underneath the outer or discharge end of the spout 13 and may be 125 partially received within the recess which is defined by the re-entrant portion of the lower section 2. When the pressure on the outer end of the operating handle 25 has been removed, the hollow valve will be re- 130

turned to the position shown in Figures 4 and 5 through the action of the spring 22 and the space within the hollow valve at the upper side of the partition plate 27 will 5 again be filled so that the device is always in condition when there is granular material within the upper section 1 to discharge substantially the same quantity of the granular material from the spout 13 each 10 time the outer end of the handle 26 is depressed.

Obviously, my invention is susceptible of embodiment in forms other than that illustrated in the accompanying drawings, and 15 I therefore consider as my own all such modifications and adaptations of the form of the device herein described as fairly fall within the scope of the appended claim.

Having thus described the invention, what 20 I claim is:—

A container comprising a tubular upper section, a tubular lower section adapted at its upper end to engage with the lower end 25 portion of said upper section, and a hopper carried by the lower section at the lower end of the upper section, a hollow valve casing secured against the under side of said hopper and having an inlet opening in register with the opening of the hopper, 30 said valve casing also having a lateral discharge opening, a discharge conduit extending from said lateral opening outwardly beyond the lower section and being inclined toward its lower end, means within said valve casing for controlling communication 35 between the first named opening of the valve casing and said spout, a rotary hollow valve having an opening in the walls thereof adapted when the rotary valve is in one position within the valve casing to register 40 with the inlet opening of the valve casing and when the rotary valve is in another position in the valve casing to register with the lateral discharge opening of the valve casing, and a partition plate 45 dividing the interior of the hollow valve into two compartments, the partition plate extending longitudinally of the valve and being inclined when the valve is in either of the two aforesaid positions thereof, said 50 partition plate sloping toward the lateral discharge opening of the valve casing when the opening of the valve is in register with said discharge opening and sloping in the opposite direction when the opening of the valve is in register with the inlet opening of the valve casing.

CHARLES LOUIS BERNIER.
